POWER OPERATED CHUCK

George A. Highborg and Harry E. Sloan, Hartford, Conn., assignors to The Cushman Chuck Company, Hartford, Conn., a corporation of Connecticut

Application November 27, 1939, Serial No. 306,277

13 Claims. (Cl. 279—1)

The present invention relates to improved power mechanism for radially moving the jaws of a power driven chuck into or out of engagement with a work piece to be supported thereby.

- 5 At present, there is commonly employed two types of mechanism for accomplishing the radial movement of the jaws of a power driven chuck. The first of these is well exemplified by the Van Hamersveld Patent No. 1,816,239 wherein a power wrench is substituted for the usual hand wrench which accompanies a standard type of chuck. As is readily apparent from said patent, the power operating means disclosed thereby merely applies mechanical power to the end of 10 a wrench in place of manual power. The second type is well exemplified by the Hay Patent No. 1,441,803 wherein a gear train is provided directly between a source of driving power and the chuck jaws. As is apparent from the Hay 15 patent, the chuck must be especially designed to include elements of the gear train, and a definite mechanical advantage is thus obtained over a power on hand operated wrench.

The present invention relates to power operated jaw actuating means falling in the second category, and the principal object of the present invention is to provide an improved mechanism of this type.

25 A still further object is a power operated jaw actuating mechanism utilizing a relatively light driving means therefor, though affording a high mechanical advantage and whereby fine adjustments of the jaws may be obtained.

30 A still further object is a mechanism of the above-indicated type which is compact, requires relatively few parts, and is both economical and efficient in operation.

Other objects will be in part obvious and in 40 part pointed out more in detail hereinafter. The invention accordingly consists in the features of construction, combination of elements, and arrangement of parts which will be exemplified in the construction hereafter set forth and 45 the scope of the application of which will be indicated in the appended claims.

In the accompanying drawings:

Figure 1 is an end view of a portion of the headstock of a lathe, looking towards the chuck, embodying the jaw actuating mechanism disclosed herein, with parts thereof in section to more clearly show the structure thereof;

Fig. 2 is a view as seen from the left of Fig. 1, also partly in section to show details of construction thereof;

Fig. 3 is an enlarged sectional view taken on the line 3—3 of Fig. 1;

Fig. 4 is an enlarged sectional view taken on the line 4—4 of Fig. 1;

Fig. 5 is an end view looking towards the chuck, 5 with portions of the chuck broken away to show details of construction; and

Fig. 6 is a sectional view of the chuck shown in Fig. 5.

Referring to the drawings, there is shown the 10 headstock 10 of a lathe; the headstock having rotatably mounted therein a spindle 12. The spindle 12 is controlled through a clutch whereby it may be connected for operation in reverse directions to a driving means, or entirely disconnected therefrom; the clutch and driving means being omitted as they may be of any well-known construction. The operation of the spindle clutch is controlled by a lever 14 extending 15 forwardly from the vertical center of the headstock and arranged for pivotal movement in a horizontal plane. The spindle 12 has secured thereto, as by bolts 16, a chuck 18; the chuck having thereon a plurality of gripping jaws 20 20 adapted to be radially moved towards and from 25 the axis of the chuck, whereby they may engage or be disengaged from a work piece carried thereby.

In accordance with the present invention, the 30 radial movement of the chuck jaws is accomplished through a gear train extending from a suitable source of power directly to the jaws and partially housed by a power or driving unit 22 and partially housed within the chuck 18; the unit 22 being so constructed that it may be 35 moved into and out of cooperative driving relation with the chuck and thus make or interrupt the continuity of the gear train.

More specifically, the driving unit 22 includes 40 a rack guide 24, a gear housing 26, and a motor 40 housing 28 joined together as a unitary structure and in which there is respectively mounted a rack 30, reduction gearing 32, and a source of power 34. As best seen from Fig. 3, the rack guide 24 is in the form of an inverted rectangular U having a top plate 36 and downwardly depending legs 38 and 40, and the inner face of each leg has integral therewith an outwardly extending rack supporting way 42. The rack 30 is also of 50 rectangular form, with each side wall thereof 50 grooved to receive a way 42 and thus mount the rack for longitudinal movement within the guide 24. To limit the longitudinal movement of the rack, there is arranged adjacent the ends of the upper surface 44 thereof spaced apart shoulders 55

46 (see Fig. 1) adapted to abut against a stop member 48 nonrotatably and removably positioned in a slot 50 cut in the top plate 36 of the rack guide.

5 The longitudinal movement of the rack 30 within the guide is accomplished by providing the interior of the rack with a threaded bore 52 adapted to receive a rotatable screw 54. For simplicity and economy in manufacture and assembly, the screw 54 not only constitutes driving means for the rack, but also functions as a part of the reduction gear between the power source and the rack. To accomplish this, the inner end 56 of the screw is receivable in the gear housing 26 and has cut thereon a pair of adjacent annular shoulders 58 and 60; the shoulder 60 being of slightly greater diameter than the shoulder 58. Mounted for free rotation on the shoulder 58 is a ring gear 62; the outer periphery thereof being provided with suitable gear teeth 64, adapted to mesh with teeth of a gear 66 carried by a shaft 68, journaled at its forward end in the gear housing 26. The rear portion of shaft 68 extends through and is journaled in the front plate 70 of the motor housing 28, and the portion thereof extending into the motor housing has splined thereon a gear 72 meshing directly with a gear 74 mounted for simultaneous rotation on the shaft 76 of the power source, thus establishing a direct drive from the power source to the ring gear 62. In the present instance, the driving source comprises a high torque, high speed, relatively low horse power motor 78, and in order to permit the use of such motor, lost motion means are provided to enable it to reach speed before directly driving the screw 54.

The desired lost motion is obtained by providing ring gear 62 with a circumferential shoulder 80 having an inner surface 82 overhanging and radially spaced from the annular shoulder 60 of the screw head. The inner surface 82 of the ring gear has cut thereon a pair of diametrically opposite teeth or radial abutments 63 adapted to contact a single tooth or abutment 83 extending radially from the shoulder 60 of the screw head. The ring gear 62 is thus capable of free rotation through approximately one hundred and eighty degrees, depending upon the direction of rotation thereof, before direct contact is made between one of the abutments carried thereby and the abutment carried by the screw head. Thus sufficient lost motion is obtained to allow the motor not only to come up to speed but to strike a sudden blow and overcome the inertia of the gear train beyond the same.

To further facilitate ease of operation, the enlarged screw head is journaled in suitable ball bearing races 90, 92, and 94; the ball bearing races 90 and 92 being arranged in suitable grooves cut in the gear housing 26 and the race 94 being arranged in a suitable groove cut in the end plate 70 of the motor housing.

65 By thus obtaining the longitudinal movement of the rack 30 from the rotary movement of the screw 54, a maximum power factor is obtained and the speed of the rack may be so controlled that extremely fine jaw adjustments may be obtained. Moreover, due to the large speed reduction obtained by properly coordinating the threaded engagement between the screw and the rack, the reduction gearing required between the motor 78 and the screw may be reduced to a minimum. The operation of the motor may be

readily controlled through means conveniently located within reach of the operator; such means being omitted herein as they may be of any desired construction.

Furthermore, by constructing the unit in the manner described, it requires but a minimum number of parts and lends itself to rapid assembly and disassembly. By removal of the stop member 48 from the top plate 36 of the rack guide and the removal of the end plate 70 of the motor housing, the screw 54 and rack 30 may be readily removed from their respective supports. Because of this, a standard rack guide may be utilized for various sizes of chuck; the required power factor and rate of movement of the rack being obtained by utilizing proper pitch for the screw and threaded bore of the rack.

As previously stated, the gear train within the unit 22 is adapted to cooperate with a gear train within the chuck 18, and this is accomplished by providing the lower face of the rack 30 with teeth 95 adapted to cooperatively engage the peripheral teeth 102 of an actuator ring 96. The actuator ring 96 is part of the gear train housed within the chuck 18, and, as best seen in Fig. 6, it is mounted for rotation on a circumferential shoulder 98 provided on the chuck body 100. The ring 96 is further provided on the radial face 104 thereof with a second set of peripheral teeth 106, which teeth are in meshing engagement with a plurality of pinions 108. The pinions 108 are radially disposed and journaled in the chuck body, and there also meshes therewith the teeth 110 of a scroll plate 112, which plate, upon being rotated, actuates the gripping jaws 20 radially in a well-known manner. The actuator ring 96, pinions 108, and scroll plate 112 thus complete an unbroken gear train from the motor 78 to the gripping jaws 20 when the rack 30 is in engagement with the actuator ring.

Because of the compactness of the unit 22, it can also be mounted directly on the headstock, thus making it within convenient reach of the operator for moving it into and out of cooperative engagement with the chuck. In order to so mount the unit, there is provided thereon a pair of spaced apart supporting brackets 114 and 116 joined together by a spacer plate 118; the bracket 116 being integrally secured and preferably cast with the rack guide 24. The brackets 114 and 116 are provided with aligned longitudinal bores adapted to receive a sleeve 120 about which the unit may be pivoted. The sleeve 120 is supported on the headstock by a pair of spaced apart brackets 122 and 124 located rearwardly of the vertical center line of the chuck and secured to the headstock in any suitable way. As it is essential that the rack 30 be mounted in proper longitudinal relationship with the actuator ring 96, the spacing of the supporting brackets 114 and 116 of the unit is such that when the device is assembled they straddle the sleeve supporting bracket 124, and thus the unit is maintained in proper longitudinal position. The foregoing means for mounting the unit facilitates assembly thereof in that it is only necessary to align the respective supporting brackets and insert the sleeve therethrough, and, if repairs are required, by simply removing the sleeve the entire unit 22 may be readily removed from the machine.

The pivoting of the unit 22 into and out of operative engagement is accomplished by a manually operated lever 126 arranged for convenient manipulation by the operator. The lever 126 is secured to one arm 128 of a bell crank 75

130, which crank is mounted for pivotal movement about a pivot pin 132 carried by an arm 135 integral with and extending upwardly from the sleeve supporting bracket 124. The other 5 arm 136 of the bell crank 130 is connected to the rack guide 24 through a toggle link 138, which link has its upper and lower ends respectively pivoted to the arm 136 and upper plate 36 of the rack guide. The toggle link 138 is of such length 10 that when lever 126 is in horizontal position, the toggle is just over dead center abutting against a stop 140, and the rack 30 is in meshing engagement with the actuator ring 96. Upon movement of the lever 126 vertically, the toggle will 15 be broken, whereupon unit 22 will be pivoted about the supporting sleeve 120, moving the rack 30 out of engagement with the actuator ring 96 and thus breaking the continuity of the gear train from the motor 78 to the gripping jaws 20. 20 It is essential that the chuck 18 be held against rotation when the unit is moved into operative position, and to accomplish this, means are provided which are automatically operative to prevent rotation of the chuck simultaneously with 25 the movement of the unit into operating position. This is accomplished by arranging in the leg 40 of the rack guide a rectangular opening in which there is positioned a block 142, the lower face of which defines a gear segment 143 consisting of three teeth adapted to move into and 30 out of meshing engagement with the peripheral teeth 144 of a chuck plate 146 secured to the chuck body by bolts 148. As best seen in Fig. 3 the block 143 is provided with a slot 145 therein 35 through which a pin 147 extends for holding same within the rack opening provided therefor. Positioned to either side of the center of the block are elongated openings 149 for receiving a spiral spring 151 for normally urging the block 40 downwardly towards the plate 146. With this construction, when the leg is moved downward and into engagement, if the teeth 143 of the block and the teeth 148 of the chuck holding plate are not in exact alignment, the springs 151 will 45 permit the block to yield until alignment is made and thus damage to the meshing parts is avoided.

The clutch holding means just described further adds to the simplicity of the structure and 50 ease of control thereof. The operator, through the manipulation of the unit control handle 126, thus simultaneously moves the rack 30 into engagement with the actuator ring 96 and the holding segment 142 into engagement with the holding plate 146. Insasmuch as both the ring 55 and holding plate have teeth disposed around the entire periphery thereof, engagement will be obtained at any point of stoppage of the chuck. Moreover, as the unit 22 is secured in 60 position by the toggle 138, a positive engagement of the cooperating holding means is assured.

The unit is further provided with means for interlocking the chuck control lever 14 in neutral position when the unit is in operating position, 65 as well as preventing the movement of the unit to operating position when the lever 14 is out of neutral position. As best seen in Fig. 2, the interlock for accomplishing the above purpose includes a lever 150 integrally secured to the guide 70 rack 24 and extending laterally therefrom toward the lever 14. There is cut adjacent the outer end of the lever 150 a downwardly facing groove 152 into which the lever 14 may be received. As readily seen from Fig. 2, when the lever 14 is 75 positioned within the groove 152, the unit 22 is

in operative position and the lever 14 cannot be moved from its neutral position. Obviously whenever the lever 14 is out of neutral position to either side of the groove 152, as indicated by dotted lines in Fig. 2, it will underlie the lower edge 154 of the lever 150 and thus prevent the unit from being moved into operative position.

Although the operation of the device is readily understandable from the foregoing, it is pointed out here that the entire control is obtained 10 through the instrumentality of the single unit operating lever 126 and that movement of this lever performs three functions—namely, it carries the rack 30 into meshing engagement with the actuator ring 96, thus establishing a continuous gear train from the motor 78 to the gripping jaws 20. It carries the gear segment 142 into engagement with the holding plate 146 of the chuck; thus restraining the chuck against rotation, and it carries the lever 150 into position 15 to interlock the clutch operating lever 14 against movement to operative position.

As many changes could be made in the above construction and many apparently widely different embodiments of this invention could be made 20 without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of 25 language, might be said to fall therebetween.

We claim as our invention:

1. In a tool of the character described, a rotatable chuck, work holding jaws movable on said chuck, an exterior toothed gear rotatably mounted on the chuck and operatively connected to the work jaws, a power unit for rotating said chuck gear including a housing, a rack slidably mounted in the housing and engageable with said rotatable gear, power means carried by the housing and operatively connected to the rack, and means supporting the power unit for pivotal movement whereby the rack may be moved into and out of meshing engagement with the rotatable gear.

2. In a tool of the character described, a rotatable chuck, work holding jaws movable on said chuck, an exterior toothed gear rotatably mounted on said chuck and operatively connected to the work jaws, an exterior toothed holding plate fixed to the chuck adjacent the gear, a power unit for rotating said chuck gear including a housing, a rack slidably mounted in the housing and engageable with the rotatable gear, power means carried by the housing and operatively connected to the rack, a rack segment carried by the housing adjacent the rack, and means supporting the power unit for pivotal movement whereby the rack and rack segment will be simultaneously moved into and out of meshing engagement respectively with the rotatable gear and holding plate.

3. In a tool of the character described, a rotatable chuck having a chuck body with peripherally extending exterior teeth, work holding jaws movable on said chuck, an exterior toothed gear rotatably mounted on said chuck and operatively connected to said work jaws, a power unit including a rack segment engageable with said peripheral teeth for non-rotatably holding said

- chuck and a slidable rack for engaging said chuck gear for rotating same to operate said chuck jaws, and means for pivoting said power unit into and out of position relative to said chuck.
5. 4. In a tool of the character described, a rotatable chuck, work holding jaws movable on said chuck, power means for operating said jaws, a gear train extending between said power means and said jaws and including a meshing drive rack and driven gear and means for moving said rack and gear relative to one another out of meshing engagement to break the continuity of said gear train.
10. 5. In a tool of the character described a rotatable chuck, work holding jaws movable on the chuck, a power unit for operating said chuck mounted for pivotal movement towards and from said chuck, power means carried thereby, a gear train extending from said power means to said chuck and including a drive rack carried by the power unit and a driven gear carried by the chuck, said rack being simultaneously movable with said power unit into and out of engagement with said gear whereby the continuity of said gear train may be made or broken.
15. 6. In a tool of the character described, a rotatable chuck, work holding jaws movable on said chuck, a power unit for moving said jaws, cooperating engageable driving means carried by said power unit and said chuck for operatively connecting said unit to said jaws, and cooperating engageable holding means carried by said unit and said chuck for nonrotatably holding said chuck upon engagement of said cooperating driving means, and means pivotally mounting said unit for movement towards and from said chuck whereby said cooperating means will be simultaneously engaged or disengaged.
20. 7. In a tool of the character described, a rotatable chuck having work holding jaws, a lever mounted on the tool for starting rotation of the chuck, a power unit pivotally mounted on said tool for movement toward and from said chuck and including drive means engageable with means on said chuck for operating the work holding jaws, holding means engageable with means on said chuck for nonrotatably holding same, means for engaging said starting lever for locking said lever in neutral position, said drive means, holding means and starting lever engaging means being simultaneously moved into and out of operative position upon pivotal movement of the power unit towards and from the chuck.
25. 8. Chuck jaw operating means comprising a housing having means for pivotally mounting it on a headstock, power means carried in the housing, a rack slidable in the housing and driven by a screw operatively connected to said power means through a lost motion connection.
9. Chuck jaw operating means comprising a housing having means for pivotally mounting it on a headstock, a high speed high torque motor carried by the housing, a rack slidable in the housing and driven by a screw operatively connected to said motor through a lost motion connection. 5
10. 10. In a tool of the character described, a rotatable chuck having work engaging means, a rotatable gear mounted on said chuck and operatively connected to said work engaging means, a power unit mounted on said tool for pivotal movement towards and from said chuck and including a rack engageable with said chuck gear and cooperating means carried by said power unit and said chuck and simultaneously operative upon engagement of said rack and gear for non-rotatably holding said chuck. 15
11. In a tool of the character described, a rotatable chuck having work engaging means, a gear carried by said chuck and operatively connected to said work engaging means, a second gear fixed to said chuck for simultaneous rotation therewith, a power unit pivotally mounted on said tool for movement towards and from said chuck and including a longitudinally movable rack engageable with said rotatable gear and a plurality of fixed teeth on said unit simultaneously engageable with said fixed gear for non-rotatably holding said chuck. 20 30
12. In a tool of the character described, a rotatable chuck having work engaging means, a gear carried by said chuck and operatively connected to said work engaging means, a second gear fixed to said chuck for simultaneous rotation therewith, a power unit pivotally mounted on said tool for movement towards and from said chuck and including a longitudinally movable rack engageable with said rotatable gear and a plurality of fixed teeth on said unit simultaneously engageable with said fixed gear for non-rotatably holding said chuck, a lever mounted on said tool for pivoting said power unit, a toggle connection between said lever and said unit movable past dead center position upon movement of said power unit into operative position whereby said unit will remain in operative position until release of the lever. 35 40 45
13. Chuck jaw operating means comprising a housing having means for pivotally mounting it on a headstock, power means carried in the housing, a rack slidable in the housing, a screw for operating said rack, a driving abutment mounted on said screw, a gear rotatably mounted on said screw and having an abutment engageable with said screw abutment and means operatively connecting said gear to said power means. 50 55
